DESIGN FOR A HAT

Charles Rothenberg, New York, N. Y.

Application August 13, 1936, Serial No. 64,395

Term of patent 3½ years

To all whom it may concern:

Be it known that I, Charles Rothenberg, a citizen of the United States of America, residing in city of New York, county of New York, and State of New York, have invented a new, original, and ornamental Design for a Hat, of which the following is a specification, reference being had to the accompanying drawing, forming part thereof.

Fig. 1 is a perspective view of a hat showing my new design.

Fig. 2 is a side elevational view of the hat shown in Fig. 1.

My design is characterized by the straight cut on the rear portion of the brim.

I claim:

The ornamental design for a hat substantially as shown and described.

CHARLES ROTHENBERG.
